Attorney

UNITED STATES PATENT OFFICE.

CHARLES SULZNER, OF AUDUBON, NEW JERSEY.

CLASP.

1,331,291.

Specification of Letters Patent. Patented Feb. 17, 1920.

Application filed April 10, 1917. Serial No. 160,954.

To all whom it may concern:

Be it known that I, CHARLES SULZNER, a citizen of the United States, and resident of Audubon, in the county of Camden and 5 State of New Jersey, have invented certain new and useful Improvements in Clasps, of which the following is a specification.

This invention relates to clasps and has more particular reference to an improved 10 type of pivoted clasp.

The invention has for its dominant object to provide a pivoted clasp for securing the free ends of bands, fabrics or tapes in a manner such as to positively prevent accidental 15 or undue disengagement of the same therefrom resulting from direct or indirect pulling, pushing or lifting of the band, etc.

It is also an object of the invention to provide a clasp which is entirely independent 20 of the material or object engaged thereby, thus allowing the clasp to be easily and quickly removed to permit use thereof in conjunction with other material or objects.

Among other aims and objects of the invention may be recited, the provision of a 25 clasp of the character mentioned with a view to compactness, and in which the number of parts are few, the construction simple, the cost of production small, and efficiency 30 and operation high.

Other and further improvements and novel details in the construction and arrangement of parts will be appreciated from the description to follow, which for a clear 35 understanding of the invention should be considered in connection with the accompanying drawings forming a part hereof and wherein the preferred embodiment of the invention is shown for the purpose of 40 illustration.

In the drawings:

Figure 1 is a top plan of my improved pivoted clasp; and

Fig. 2 is a longitudinal section there- 45 through taken on the line 2-2 of Fig. 1.

Similar characters of reference are employed in all of the above described views to indicate corresponding parts.

Referring now more specifically to the several figures of the said drawings, it is to be noted that I have shown, in the present embodiment, my improved clasp as being particularly adapted for use in connection with circular garters whereby the free ends of the 55 material may be securely united although, it is to be understood that the invention is

not limited to this field. There is provided a curved base plate 5 formed, preferably, of sheet metal or other like material whose opposite side edges are provided with integral 60 upstanding apertured bearing lugs 6, whereby the lock or lever of the clasp, which will be subsequently described, may be properly supported therebetween. A plurality of transversely disposed projections 10 are 65 struck upwardly from the base plate 5 and are of a height sufficient to permit the same to penetrate or partially penetrate the super- 70 posed opposite ends of the garter material designated G.

A lever 7 having a downwardly extending lip portion 8 formed thereon is pivotally mounted between the apertured bearing lugs 6, through the medium of oppositely disposed lugs 9, formed thereon and passing 75 through the said bearing lugs 6. To facilitate engagement with the free extremity of the lever 7, an upwardly curved thumb piece 16 is formed thereupon, while to rigidify the same throughout its length a con- 80 cavo-convex portion 17 is stamped therein and if desired, may have suitable ornamental matter applied or engraved upon the exposed face thereof. To insure positive engagement of the lip portion 8 of the lever 85 with the garter material, the lower edge thereof is serrated as at 13 and, obviously, when moved into engagement with the garter material will engage the same in a manner to prevent accidental moving of the 90 lever to releasing position.

It may be here noted, that the transversely disposed projections formed upon the base plate 5 are arranged in proximity of the serrated portion of the binding lip 8 and as a 95 consequence, when the said binding lip is moved into engagement with the garter material, the free ends of the same will be positively impinged upon, about and betwixt the said teeth. Hence, such pulling, pushing 100 or lifting of the material as may occur during the use of the same will be prevented from forcing the lever 7 to open or releasing position or the disengaging of the ends of the material from the teeth 10.

Should for any reason, the lever 7 be accidentally moved to its open or releasing position, it is manifest that the free ends of the garter material by being affixed upon, about and betwixt the transversely disposed projections 10 would prevent separating of 110 the overlapping ends of the same.

As hereinbefore indicated, I do not wish to be understood as confining the invention to the particular embodiment chosen for illustration, herein, nor to the exact construction, arrangement and adaptation of the parts shown and described, but I reserve the right to make any changes and alterations that fairly fall within the spirit and scope of the invention.

10 I claim:

A clasp including a base plate having portions struck upwardly from the base plate to form prongs arranged in spaced transverse alignment and adjacent the central portion 15 thereof, a lever pivotally connected with

the base midway the length thereof and having its free end extending past one end of the base plate when in locking position, a flange on the pivoted end portion extending toward the plate and adapted when in locking position to move the fabric about and into engagement with the upstruck portions or prongs, and said lever having a centrally located convexed portion formed therein between the pivoted and free ends to reinforce and increase the rigidity of the same for the purpose set forth.

20 In testimony whereof, I affix my signature hereto.

25 CHARLES SULZNER.
